(57) CLAIM

The ornamental design for a holiday vest, as shown and described.

DESCRIPTION

FIG. 1 is a front perspective view of a first embodiment of the holiday vest;

FIG. 2 is a front elevation view of the FIG. 1 article;

FIG. 3 is a right side elevation view of the FIG. 1 article;

FIG. 4 is a left side elevation view of the FIG. 1 article;

FIG. 5 is a rear elevation view of the FIG. 1 article;

FIG. 6 is a top plan view of the FIG. 1 article;

FIG. 7 is a bottom elevation view of the FIG. 1 article;

FIG. 8 is a front perspective view of a second embodiment of the holiday vest;

FIG. 9 is a front elevation view of the FIG. 8 article;

FIG. 10 is a right side elevation view of the FIG. 8 article;

FIG. 11 is a left side elevation view of the FIG. 8 article;

FIG. 12 is a rear elevation view of the FIG. 8 article;

FIG. 13 is a top plan view of the FIG. 8 article; and,

FIG. 14 is a bottom elevation view of the FIG. 8 article.

The broken lines located near the pockets and back of the collar are for illustrating unclaimed stitching, while the broken lines elsewhere are for illustrating environmental structure and form no part of the claimed design.

1 Claim, 6 Drawing Sheets
